UNITED STATES PATENT OFFICE.

JULIAN H. FAW, OF NEW YORK, N. Y.

WRENCH.

Application filed January 11, 1923. Serial No. 612,058.

To all whom it may concern:

Be it known that I, JULIAN H. FAW, a citizen of the United States, residing at New York, in the county and State of New York, have invented certain new and useful Improvements in Wrenches, of which the following is a full, clear, and exact specification.

This invention relates to wrenches and particularly to socket wrenches having angular inclosing sockets for the nuts or other parts to be turned.

It is the object of the invention to provide a wrench of this type which is simple in construction, comprising only two parts, and capable of easy operation for quickly applying or removing nuts or similar parts. The invention provides for applying considerable leverage when tightening or loosening a nut or bolt, and for very quickly turning the same before tightening or after loosening when no great leverage or power is required.

These objects are attained by the use of a simple form of socket member and a straight handle bar of angular cross section. The socket member has a wrench socket in one end, and a transverse passage and an axial passage in its other end portion, the axial passage being of a shape to be engaged by the handle bar when one end portion of the latter is inserted therein for spinning the socket member quickly to or from the tightening position of the nut by rolling said handle bar between the palms of the hands. The transverse passage in the socket member is designed to be engaged by the end portion of the handle bar when greater leverage is desired for tightening or loosening the nut.

In the accompanying drawings, wherein similar reference characters are used to designate corresponding parts in the several views:—

Figure 1 is an elevation of the wrench arranged for tightening or loosening a nut.

Figure 2 is an elevation of the wrench arranged for spinning a nut quickly to or from tightening position.

Figure 3 is a section on the line III—III of Figure 2, showing the wrench applied to a nut.

Figure 4 is a section on the line IV—IV of Figure 5.

Figure 5 is a plan view of the wrench as

shown in Figure 1, part of the handle bar being broken away, and

Figure 6 is a lower end view of the socket member of the wrench.

The socket member 1 is preferably made of a single piece of suitable metal and may be generally cylindrical in shape, as shown. The handle bar 2 may be of suitable length and of any angular cross section, such as the hexagon shape illustrated. The transverse passage 3 in the upper end portion of the socket member is preferably circular in cross section, or otherwise shaped to receive the end portion of the handle bar in any position of its polyface sides, so that the insertion of said bar into said passage is facilitated and the consumption of time which might be required to introduce the handle bar into a correspondingly shaped transverse passage is avoided.

The axial passage in the upper end of the socket member is illustrated at 4, the same being of corresponding shape to the cross section of the handle bar or of other suitable form to insure the turning of the socket member with the handle bar when the latter is in the position shown in Figs. 2 and 3. The angular socket 6 in the lower end of the socket member 1 may be shaped to fit any type of nut or bolt, and a round bore 5 may extend through the socket member between said socket 6 and the passage 4 if desired.

In operation, when a nut 7, Fig. 3, is to be applied to a bolt 8 for tightening against an abutment 9, the handle bar 2 is inserted into the axial passage 4 of the socket member and said nut quickly spun down to tightening position by rolling said handle bar between the palms of the hands. The handle bar is then removed from the axial passage 4 and slipped into the transverse passage 3 in the socket member, as shown in Figs. 1 and 5, whereupon a short turn with the leverage provided by the radially extending handle bar will tighten said bolt against the abutment 9.

For loosening a tightened nut the handle bar is arranged in the transverse passage 3, and after loosening, said handle bar is inserted in the axial passage 4 and rolled between the palms of the hands for quickly spinning the nut off of the bolt. It will thus be seen that with the simple form of one-piece socket member and straight polyface handle bar shown

nuts may be applied and tightened, or loosened and removed from their bolts more expeditiously than with prior forms of wrenches of more complicated and expensive construction.

I claim:

1. A wrench comprising a socket member having a continuous axial passage extending therethrough, the lower end portion of said passage constituting the nut-engaging recess, the upper end portion of said passage being concentric with said nut-engaging recess and also of angular cross-sectional contour, and a handle bar of similar angular cross-sectional contour to fit said recess in the upper end of said socket member, whereby said socket member may be spun for quickly turning the nut to or from tightening position by rolling said handle bar between the palms of the hands, said socket member also having a transverse passage extending across the axial passage therein to receive said handle bar for tightening or loosening a nut.
2. A wrench comprising a socket member having a continuous axial passage extending therethrough, the lower end portion of said passage constituting the nut-engaging recess, the upper end portion of said passage being concentric with said nut-engaging recess and also of angular cross-sectional contour, and a handle bar of similar angular cross-sectional contour to fit said recess in the upper end of said socket member, whereby said socket member may be spun for quickly turning the nut to or from tightening position by rolling said handle bar between the palms of the hands, said socket member also having a transverse passage extending across the axial passage therein and opening on both sides of said member to receive said handle bar for tightening or loosening a nut.
3. A wrench comprising a socket member

having a continuous axial passage extending therethrough, the lower end portion of said passage constituting the nut-engaging recess, the upper end portion of said passage being concentric with said nut-engaging recess and also of angular cross-sectional contour, and a handle bar of similar angular cross-sectional contour to fit said recess in the upper end of said socket member, whereby said socket member may be spun for quickly turning the nut to or from tightening position by rolling said bar between the palms of the hands, said socket member also having a transverse passage extending across the axial passage therein and opening on both sides of said member to receive said handle bar for tightening or loosening a nut, said transverse passage being of a size to receive said handle bar in any rotated position thereof.

4. A wrench comprising a socket member having a continuous axial passage extending therethrough, the lower end portion of said passage constituting the nut-engaging recess, the upper end portion of said passage being concentric with said nut-engaging recess, and also of angular cross-sectional contour, and a handle bar of similar angular cross-sectional contour to fit said recess in the upper end of said socket member, whereby said socket member may be spun for quickly turning a nut to or from tightening position by rolling said bar between the palms of the hands, and socket member also having a transverse passage extending across the axial passage therein and opening on both sides of said member to receive said handle bar for tightening or loosening a nut, said transverse passage being round in cross-section for the purpose specified.

In testimony whereof I have signed my name to this specification.

JULIAN H. FAW.
